UNITED STATES PATENT OFFICE.

PAUL M. HOTCHKIN, OF CHICAGO, ILLINOIS.

LIGHTING FIXTURE.

Application filed August 29, 1921. Serial No. 496,212.

To all whom it may concern:

Be it known that I, PAUL M. HOTCHKIN, a citizen of the United States, residing at Chicago, in the county of Cook and State of Illinois, have invented certain new and useful Improvements in Lighting Fixtures, of which the following is a specification.

This invention relates to lighting fixtures for indirect electrical illumination, and is particularly concerned with fixtures of the suspended type.

Suspended indirect lighting fixtures include a canopy, a bowl, a reflector, and a connection between the canopy and bowl for sustaining the bowl from the canopy as well as for conveying electrical current to and from the illuminating element or elements within the bowl. The usual construction of suspended fixtures, however, is such that unsightly connections are employed for holding the reflector within the bowl, thus precluding symmetry of design and relation of the parts in the fixture. Furthermore, the ordinary construction of suspended fixture is such that access to the interior of the bowl is difficult, and this interferes with cleaning of the interior of the fixture, and likewise with removal of the reflector or the illuminating element when such is desired. The conditions recited particularly apply to those fixtures in which a single lamp is employed as the source of light.

The present invention has as its primary object the provision of a lighting fixture which will overcome the objections above recited, its construction being such as to free the same from unsightly suspensory connections and at the same time permit access readily to be had to the interior of the bowl, whether for cleansing purposes, removal or repair of the reflector held therein, or removal of the lamp employed with the fixture.

A further object of the invention is to provide a lighting fixture having novel and efficient means for holding the reflector within the bowl against displacement therefrom and to sustain the same free from contact with the bowl.

Other objects and advantages will appear as the nature of the improvements is better understood, the invention consisting substantially in the novel construction, combination and arrangement of parts herein- after fully described, illustrated in the ac-

companying drawings, and finally pointed out in the appended claims.

Two particular embodiments of the invention are presented in the disclosure herein, but these are not to be taken in a limiting or restrictive sense, the same being intended to delineate to the art an appropriation of the concept and its application in practical forms to the purposes for which the invention is contemplated. 65

In the drawings,

Fig. 1 is a side elevation, partly in section, of a lighting fixture constructed in accordance with the present invention;

Fig. 2 is a sectional plan view thereof 70 taken on the line 2—2 of Fig. 1;

Fig. 3 is a transverse sectional view of the bowl portion of the fixture on the line 3—3 of Fig. 2;

Fig. 4 is a top plan view of the socket shell;

Fig. 5 is a sectional plan view illustrating another form of the fixture;

Fig. 6 is a sectional view on the line 6—6 of Fig. 5; and 80

Fig. 7 is a fragmentary sectional view, showing in enlarged detail a portion of the fixture shown in Fig. 3.

Referring in detail to the accompanying drawings, and more particularly to Figs. 1, 2 and 3 thereof, the numeral 10 designates the canopy of the herein-described fixture. Any approved construction of canopy may be used so that it is unnecessary to set forth the specific construction 90 thereof. Extending downwardly from the canopy 10 is the chain 11 at the lower end of which is supported a socket shell 12 within which is disposed any approved form of interior socket 13 to which is applied a lamp 14 as the illuminating element. 95 As above indicated, the invention is particularly concerned with suspended fixtures in which a single lamp is employed as the illuminating element, although the invention is applicable to those forms of fixtures where more than one lamp is employed for this purpose.

At the exterior of the socket shell 12 and at appropriate points thereon, is a plurality 105 of vertically disposed receiving sleeves 15. Preferably, these sleeves are formed integral with the shell 12. Arranged within each of the receiving sleeves 15 is the vertical extension of a supporting arm 16, the hori- 110

zontal extension of which arm 16 projects in a radial direction, as clearly seen in Fig. 2. Any number of the supporting arms 16 may be employed, but three of the same are shown in the drawings and are sufficient for the purposes for which they are intended. The arms 16 are formed of metal and have a certain degree of inherent resiliency. Their vertical extensions are held within the sleeves 15 by fastening screws 17, and said arms may be adjusted vertically within said sleeves so that the bowl of the fixture may be supported at varying distances from the shell 12.

The bowl is designated by the numeral 18. This is formed preferably of opaque material, such as any desired metal, and within said bowl 18 is disposed a reflector 19 of any approved construction. However, a preferred form of reflector is that of glass with a silver mirrored back to constitute the reflecting element thereof. Obviously, the reflector 19 partakes of the general configuration of the bowl 18.

Within the bowl 18, and spaced at suitable points around the same, is a plurality of reflector holders 20. Each of said holders comprises a fastening clip 21 and a supporting clip 22. The fastening clip 21 has an upwardly extending flange which abuts against the interior of the upper edge of the bowl 18, and is fastened thereto either by riveting, spot-welding, or other equivalent means. The fastening clip 21 has a centrally disposed slot 23 at its inner edge, and this edge, at the end portions thereof, is provided with downwardly extending flanges 24. The supporting clip 22 of each of the holders 20 has a T-shaped head 25 at its outer end designed to fit beneath the fastening clip 21 and to be engaged by a fastening screw 26 fitted in the slot 23 of the clip 21. The screw 26 thereby effectually holds the fastening and supporting clips together, and slight adjustment between the two may be effected thereby. At the inner portion of the fastening clip 22 is an inclined engaging lip 27 against which the edge of the reflector 19 is adapted to rest, and between the T-head 25 and the engaging lip 27 is an offset 28 having a T-shaped slot 29 formed therein. The slot 29 is adapted to receive a T-shaped locking head 30 formed on the horizontal extension of the supporting arm 13 which cooperates with the holder 20, and by the inherent resiliency of the arm 16 the locking head 30 is held within the offset 28 after the head has been introduced therein through the T-shaped slot 29. This inherent resiliency of the supporting arms 16 also has a tendency to draw the engaging lips 27 of the holders 20 towards the center of the fixture, and thereby passes the lips against the edges of the reflector 19 sup-

porting the same free from contact with the bowl 18. To disengage the locking heads 30 from the T-shaped slots 29 it is necessary to force the arms 13 outwardly in order to project the locking heads 30 thereof through the slots 29 to a point where said heads will clear the offsets 28, whereupon the holders 20 are freed from engagement with the arms 13 to permit detachment of the bowl 18 therefrom. As illustrated in dotted lines in Fig. 3, when one of the arms 13 has been freed from its locking relation with the holder 20 with which it cooperates, the bowl 18 and the reflector 19 are free to swing downwardly to an inclined position, the other two supporting arms acting as pivots upon which the bowl thus may swing. This positions the bowl for ready access to the interior thereof, and the same thereby may be easily cleaned, the lamp may be removed and replaced, or the reflector may be withdrawn from the bowl.

For the convenient and detachable connection of the shell 12 to the chain 11 the former is provided at its upper end with a ball-like head 31 formed of a pair of spaced lugs 32 between which is received the lower terminal link of the chain 11. These lugs have aligned perforations in which is fitted a connecting screw 33 or the like by which the chain is detachably engaged and held between said lugs 32, and on which the socket is pivotally suspended. Formed in the upper end of the shell 12, and in communication with the space between said lugs 32, is an elongated opening 34 through which the wires (not shown) leading from the canopy 10 to the socket 13 are passed. The opening 34 is formed at the time the shell 12 is made, which preferably is done by die casting.

In Figs. 5 and 6 is disclosed another form of the invention. In the main this form is substantially the same as that disclosed in Figs. 1, 2 and 3, but the reflector holder is slightly modified in order to adapt the form in Figs. 5 and 6 for use in smaller bowls or with smaller reflectors. The attaching clip 21 of the changed form is the same as the attaching clip in the other form, and it includes the fastening screw 26 to hold the supporting clip 35 in position on the fastening clip. But the supporting clip in the form illustrated in Figs. 5 and 6 is of increased length, and the engaging lip 36 extends downwardly from the inner end of the clip 35. At the point of joinder of the engaging lip 36 with the supporting clip 35 a T-shaped slot 37 is formed, and said slot receives the locking head 30 of the cooperating supporting arm 16 in order to connect the arms 16 with the reflector holders.

The screw 26 being anchored in the supporting clips 22 and 35 of the two forms of

reflector holders easily may enter and leave the slots 23 in the relative movement of the clips 21 and 22 of the one form, and the clips 21 and 35 of the other, or move along the slots 23 when adjustment of the clips 22 and 35 is effected.

In connection with the foregoing it will be observed that the holders 20 perform the function not only of supporting the reflector

- 10 19 within the bowl 18, but they also constitute the means by which the supporting arms 16 are connected to the bowl 18. Inasmuch as the holders 20 lie wholly within the bowl 18, and are positioned below the upper edge 15 thereof, there is no unsightly appearing connections, and the symmetry of the fixtures thereby is enhanced. Furthermore, by engagement of the arms 16 with the holders 20 the inherent resiliency of said arms is 20 exerted to press the engaging lips of the several holders against the edges of the reflector so as to yieldingly support the latter within the bowl, and by reason of the horizontal extensions of the arms 16 lying above 25 the edges of the reflector 19 the latter also is prevented from being displaced upwardly from the bowl until the arms 16 have been freed from engagement with the holders 20.

In assembling the herein-described fixture, 30 it will be obvious that the reflector 19 is positioned on the holders 20 with its edges in contact with the engaging lips 27. Each of the arms 16 is then extended outwardly so as to bring its locking head 30 into engagement with the T-shaped slot 29 of the cooperating holder 20. On release of holding pressure from the arm 16 its resiliency causes the same to spring backwardly and draw the locking head 30 into the slot 29. 35 10 When all of the arms 16 thus have been engaged with the holders 20 the reflector 19 will be supported properly within the bowl, and the bowl likewise will be held in suspended relation to the shell 12 and the lamp 40 14 carried thereby. To release the bowl and reflector from engagement with the arms 16 a reversal of the operation just described only is necessary, and if access be desired to the interior of the reflector or bowl, as previously explained, such may be had by 45 simply releasing one of the arms 16 from its operating holder 20, whereupon the bowl may be canted downwardly, as indicated by dotted lines in Fig. 3 and access to its interior then effected.

I claim:

- 1. In a lighting fixture of the class described, the combination with a suspensory device, a bowl, and a reflector within the 50 bowl, of a plurality of inwardly directed holders associated with said bowl and provided with depending engaging lips against which said reflector is adapted to seat for supporting the reflector within the bowl, and a plurality of supporting arms associated

with said suspensory device and having detachable engagement with said holders, said supporting arms being formed of resilient material, the inherent resilience of which tends to spring the arms toward the center 70 of the fixture to preserve engagement of the arms with the holders and likewise maintain contact of the engaging lips and the holders with said reflector.

2. In a lighting fixture of the class described, the combination with a suspensory device, a bowl, and a reflector arranged within said bowl, of a plurality of inwardly extending holders carried by said bowl, said holders being provided with depending engaging lips against which the reflector is seated and by which the same is supported within the bowl, said holders being provided with interlocking openings, and a plurality of supporting arms arranged 80 within said suspensory device of the bowl, said arms including vertical extensions connected to said suspensory device and horizontal radial extensions having locking heads adapted to be received by the interlocking openings of said holders, said supporting arms being formed of resilient material the inherent resilience of which is 85 exerted inwardly of the bowl and serves to maintain the locking heads of the arms in 90 engagement with said interlocking openings.

3. In a lighting fixture of the class described, the combination with a suspensory device, a bowl, and a reflector within the bowl, of holders mounted at the edges of the bowl and extending inwardly therefrom, each of said holders including an attaching clip, a supporting clip, and means for holding said clips in engaged relation, the supporting clips being engaged by the reflector 100 and serving to sustain the reflector in suspended position within the bowl, and connections between said holders and said suspensory device.

4. In a lighting fixture of the class described, the combination with a suspensory device, a bowl, and a reflector within the bowl, of holders mounted at the edges of the bowl and extending inwardly therefrom, each of said holders including an attaching clip, a supporting clip, and means for holding said clips in engaged relation, the supporting clips being provided with depending lips engaged by the reflector and serving to sustain the reflector in suspended 110 position within the bowl, and connections between said holders and said suspensory device.

5. In a lighting fixture of the class described, the combination with a suspensory device, a bowl, and a reflector within the bowl, of holders mounted at the edges of the bowl and extending inwardly therefrom, each of said holders including an attaching 125 clip, a supporting clip, and means for hold-

- ing said clips in engaged relation, the supporting clips being engaged by the reflector and serving to sustain the reflector in suspended position within the bowl, and supporting arms connected to said suspensory device and detachably connected to the supporting clips of said holders, said arms being formed of resilient material the inherent resilience of which is exerted to maintain engagement of the arms with said holders.
6. In a lighting fixture of the class described, the combination with a suspensory device, a bowl, and a reflector within the bowl, of horizontally disposed holders mounted at the edges of the bowl and extending inwardly therefrom, each of said holders including an attaching clip, a supporting clip, and means for holding said clips in engaged relation, the supporting clips being engaged by the reflector and serving to sustain the reflector in suspended position within the bowl, and connections between said holders and said suspensory device.
7. In a lighting fixture of the class described, the combination with a suspensory device, a bowl, and a reflector within the bowl, of horizontally disposed holders mounted at the edges of the bowl and extending inwardly therefrom, each of said holders including an attaching clip, a supporting clip, and means for holding said clips in engaged relation, the supporting clips being provided with depending lips engaged by the reflector and serving to sustain the reflector in suspended position within the bowl, and connections between said holders and said suspensory device.
8. In a lighting fixture of the class described, the combination with a suspensory device, a bowl, and a reflector within the bowl, of holders mounted at the edges of the bowl and extending inwardly therefrom, each of said holders including an attaching clip, a supporting clip, and pin and slot connections between said clips for permitting relative adjustment, the supporting clips being engaged by the reflector and serving to sustain the reflector in suspended position within the bowl, and connections between said holders and said suspensory device.
9. In a lighting fixture of the class described, the combination with a suspensory device, a bowl, and a reflector within the bowl, of holders mounted at the edges of the bowl and extending inwardly therefrom, each of said holders including an attaching clip, a supporting clip, and pin and slot connections between said clips for permitting relative adjustment, the supporting clips being engaged by the reflector and serving to sustain the reflector in suspended position within the bowl, and connections between said holders and said suspensory device.
10. In a lighting fixture of the class described, the combination with a suspensory device, a bowl, and a reflector within the bowl, of holders mounted at the edges of the bowl and extending inwardly therefrom, each of said holders including an attaching clip, a supporting clip, and pin and slot connections between said clips for permitting relative adjustment, the supporting clips being engaged by the reflector and serving to sustain the reflector in suspended position within the bowl, and connections between said holders and said suspensory device.

11. In a lighting fixture of the class described, the combination with a suspensory device, a bowl, and a reflector within the bowl, of holders mounted at the edges of the bowl and extending inwardly therefrom, each of said holders including an attaching clip, a supporting clip, and pin and slot connections between said clips for permitting relative adjustment, the supporting clips being engaged by the reflector and serving to sustain the reflector in suspended position within the bowl, and supporting arms connected to said suspensory device and detachably connected to the supporting clips of said holders, said arms being formed of resilient material the inherent resilience of which is exerted to maintain engagement of the arms with said holders.

In testimony whereof I have hereunto subscribed my name.

PAUL M. HOTCHKIN.
